UNITED STATES PATENT OFFICE.

HARRY E. MITCHELL, OF SAN FRANCISCO, CALIFORNIA.

PROTECTOR BOOT FOR GEAR-SHIFT LEVERS.

Application filed September 15, 1924. Serial No. 737,828.

To all whom it may concern:

Be it known that I, HARRY E. MITCHELL, a citizen of the United States, residing at San Francisco, in the county of San Francisco and State of California, have invented 5 certain new and useful Improvements in Protector Boots for Gear-Shift Levers, of which the following is a specification.

This invention relates to improvements in 10 protector boots for gear shift levers and the transmission lock associated therewith, and has for its principal object to provide a simple and efficient means for protecting the clothes of the person operating an auto- 15 mobile from coming in contact with the grease contained within the ball and socket connection and the lower portion of the gear shift lever.

A further object of the invention is to 20 provide a protector boot of the above mentioned character, which will not only protect the operator's clothes from becoming soiled, but will also prevent any foreign substance entering the ball and socket of 25 the gear shift lever.

A still further object of the invention is to provide a protector boot of the above mentioned character, which will completely enclose the lower portion of a gear shift 30 lever and the transmission lock usually associated therewith, means being provided for gaining access to the transmission lock whenever necessary.

A still further object of the invention is 35 to provide a protector boot of the above mentioned character, which is simple in construction, inexpensive, strong and durable, and further well adapted for the purpose for which it is designated.

40 Other objects and advantages of this invention will become apparent during the course of the following description.

In the accompanying drawing, forming a part of this specification, and in which 45 like numerals designate like parts throughout the same:

Figure 1 is a longitudinal sectional view of the protector boot embodying my invention, showing the same in use.

50 Figure 2 is a top plan view thereof, and

Figure 3 is a sectional view, taken approximately on the line 3—3 of Figure 2.

In the drawing, wherein for the purpose of illustration is shown the preferred embodiment of my invention, the numeral 1 designates generally my improved protector

boot, and the same comprises a piece of leather 2, which is of U-shaped configuration in top plan, the upper edges of the side of the U-shaped leather piece 2 being cut 60 away, as clearly illustrated in Figure 2. An additional strip of leather 3 is disposed between the upper free edges of the U-shaped member 2 and the edges of the strip 3 are disposed outwardly, as illustrated at 65 4, and are fixed to the inner side portion of the leather member 2 as is illustrated at 5.

The portion of the strip 3 which is disposed adjacent the ground portion of the 70 U-shaped leather member 2 is provided with an opening 6 through which extends the gear shift lever 7. The lower portion of the gear shift lever including the ball and socket connection designated generally by 75 the numeral 8, is disposed within the boot as also clearly illustrated in Figure 1. The forward portion of the U-shaped leather member 2 and the forward portion of the cover strip 3 completely encases the trans- 80 mission lock designated generally by the numeral 9, which is associated with the gear shift lever, in the well known manner.

Access to the gear shift lock 9 by the insertion of a key therein is had by providing 85 an opening 10 in the cover strip 3, and a pivoted flap 11 normally keeps the opening 10 closed.

In order to support the leather boot in proper position around the lower portion 90 of the gear shift lever, and the transmission lock therefor, a substantially metallic reinforcing plate, such as is shown at 12, is disposed on the inner side of the leather boot, and this reinforcing plate is of the same con- 95 figuration as the U-shaped leather boot 2, the upper edge of the metallic reinforcing plate terminating at a point below the down- wardly turned side edges 5 of the cover strip 3.

The protector boot is secured in position over the lower portion of the gear shift lever and the transmission lock by means of the plate 13 which is adapted to be secured on the floor board of the motor vehicle below the usual corset or covering for the floor board and the plate 13 is provided with an upstanding flange 14, which is secured to the inner side of the leather boot 2 and the metallic reinforcing plate 12, as at 15.

The provision of a protector boot of the above mentioned character is especially de-

signed for preventing the clothes of the operator of the automobile from coming in contact with the grease around the lower portion of the gear shift lever, and further-
5 more will prevent any dirt from coming in contact with the grease, which often results in serious injury to the transmission mechanism. A device of the above mentioned character is especially adapted for use upon
10 automobiles, which are driven by ladies, whereby their skirts will not be soiled from the grease around the ball and socket and the gear shift lever. A protector boot of the above mentioned character may further-
15 more be readily and easily placed in position over the lower portion of a gear shift lever, and will not, in any way, interfere with the operation of the lever.

While I have shown the preferred embodiment of my invention, it is to be understood that various changes in the size, shape, and arrangement of parts may be resorted to without departing from the spirit of the invention and scope of the appended claims.

Having thus described my invention, what 25 I claim is:

1. A protector boot for gear shift levers comprising a substantially U-shaped casing extending around the lower portion of the lever, a covering strip having the side edges 30 thereof disposed downwardly and fixed to the inner face of the U-shaped casing, said covering strip having an opening through which the gear shift lever projects and a U-shaped reinforcing plate secured to the 35 inside of the casing.

2. A protector boot comprising a substantially U-shaped casing, a covering strip having the side edges thereof disposed downwardly and fixed to the inner face of the 40 U-shaped casing, said covering strip having an opening, a U-shaped reinforcing plate secured to the inside of the casing, and an attaching plate having an upwardly disposed flange thereon secured to the inner 45 side of the reinforcing plate.

In testimony whereof I affix my signature.
HARRY E. MITCHELL.
